UNITED STATES PATENT OFFICE.

WILLIAM R. DELANEY, OF NEW YORK, N. Y.

DISPLAY-BOX FOR NECKWEAR.

SPECIFICATION forming part of Letters Patent No. 760,431, dated May 24, 1904.

Application filed August 9, 1902. Serial No. 119,105. (No model.)

To all whom it may concern:

Be it known that I, WILLIAM R. DELANEY, a citizen of the United States, residing at New York, in the county and State of New York, 5 have invented certain new and useful Improvements in Display-Boxes for Neckwear, of which the following is a specification.

This invention relates to display-boxes especially adapted for the reception and display 10 of neckwear of the class known as "Teck" scarfs; and its object is to provide a box for the purpose stated which may be manufactured at small cost and will effectively serve to support the scarfs in proper position.

15 Heretofore packing and display boxes for scarfs have been provided with partitions conforming to the contour of the scarfs; but such boxes are objectionable for the reason that the pasteboard partitions are each formed 20 separately and separately secured to the bottom of the box. The present invention avoids the objection referred to by constructing all of the dividing-partitions of the box from a single integral blank of pasteboard or other 25 suitable material, which is folded and pasted to form connected partitions, thus enabling all of said partitions to be placed within the box at the same time and secured to the bottom thereof.

30 The construction of the improvement will be fully described hereinafter in connection with the accompanying drawings, which form part of the specification, and its novel features will be particularly set forth in the appended 35 claims.

In the drawings, Figure 1 is a plan view of 40 a blank from which the box-partitions are formed. Fig. 2 is a perspective view of the blank after it is folded and pasted ready for attachment to the box; and Fig. 3 is a plan view of a box with the folded blank in position therein, the box-cover being removed.

45 Corresponding parts in all the figures are denoted by the same reference characters.

The reference-numeral 1 designates a blank 50 of pasteboard of rectangular form, formed with parallel longitudinal creases to form the top portion 2 and sides 3 and 4 of the partition and the edge flaps 5 and 6, by means of

55 tom of the box. The blank is also formed with creases 7 at right angles to the longitudinal creases and is slotted transversely at the points 8 between the creases to form flaps 9. At the points 10 the blank is cut out to form 60 openings having oppositely-inclined walls 11, and the top section 2 is slotted diagonally adjacent to the inclined walls of the openings to form triangular flaps 12 on the tops of the flaps 9. The side portion 4 of the blank is 65 formed with parallel slits to form tongues 13. The blank constructed as thus shown and described is folded in the manner now to be explained to form the partitions. The sides 3 and 4 are folded down to vertical position, the 70 triangular flaps 12 are folded down to horizontal position, the flaps 9 folded around to vertical diagonal position, bringing the flaps 12 under the horizontal tops 2, to which they are secured by adhesive material to secure the 75 vertical diagonal flaps in position. The edge flaps 5 and 6 are then folded to horizontal position for attachment to the bottom of the box. The tongues 13 are also folded to horizontal position, with their free ends projecting 80 slightly under the adjacent edge of the securing-flap 5. The entire attachment is secured to the bottom of the box by adhesive material applied to the under surface of the flap 6 and by eyelets 14, inserted through the edge 85 of the flap 5 and the ends of the tongues 13.

It will be observed that all of the several partitions (four being shown in the drawings) are formed from a single blank and that said partitions are all placed in the box at the 85 same time and secured thereto.

The number of partitions may be varied, as of course the invention is not restricted to the number shown, and the construction of the blank may be modified to provide any desired number of partitions, the essential feature being that inclined sides are provided between the partitions to conform to the shape of the upper ends of the scarfs.

The important advantages of the improvement are that a complete attachment is provided from a single blank with little labor and a trifling waste of material and that the same may be secured in place within the box with much less work and in less time than is 100

required for adjusting and securing the ordinary separate disconnected partitions.

I would have it understood that the invention includes not only the specific construction shown in the drawings, but also all such changes and modifications thereof as may fall within the terms and scope of the following claims.

Having thus described my invention, I claim
10 and desire to secure by Letters Patent—

1. An attachment for neckwear-boxes, comprising a series of partitions formed from a single blank and having horizontal edge flaps, vertical sides, horizontal tops and vertical 15 diagonal flaps having horizontal flaps on their upper edges connected to the tops, substantially as described.

2. An attachment for neckwear-boxes, comprising a series of partitions formed from a single blank and having horizontal edge flaps, vertical sides, horizontal tops, vertical diagonal flaps having horizontal flaps on their upper edges connected to the tops, and horizontal 20 tongues between the partitions connecting the edge flaps, substantially as described.

3. An attachment for neckwear-boxes, comprising a series of partitions formed from a single blank and having horizontal edge flaps, vertical sides, and horizontal tops, said sides 25 along one side of the partitions having vertical diagonal flaps, substantially as described.

4. An attachment for neckwear-boxes, com-

prising a series of partitions formed from a single blank and having horizontal edge flaps, vertical sides, and horizontal tops, said sides 35 along one side of the partitions having vertical diagonal flaps provided with horizontal flaps on their upper edges connected to the tops, substantially as described.

5. An attachment for neckwear-boxes, comprising a series of partitions formed from a single blank and having horizontal edge flaps, one of said edges having horizontal tongues 40 between the partitions connected to the other edge, vertical sides, and horizontal tops, said 45 sides along one side of the partitions having vertical diagonal flaps, substantially as described.

6. An attachment for neckwear-boxes, comprising a series of partitions formed from a single blank and having horizontal edge flaps, one of said edges having horizontal tongues between the partitions connected to the other edge, vertical sides, and horizontal tops, said 50 sides along one side of the partitions having vertical diagonal flaps having horizontal flaps on their upper edges connected to the tops, substantially as described.

In testimony whereof I have signed my name
in the presence of the subscribing witnesses.

WM. R. DELANEY.
